His Attorneys.

UNITED STATES PATENT OFFICE.

REINHARD PLUEMACHER, OF SUNBURY, PENNSYLVANIA, ASSIGNOR TO SUSQUE-HANNA SILK MILLS, OF NEW YORK, N. Y., A CORPORATION OF NEW YORK.

SELF-THREADING SLUB CATCHER FOR AUTOMATIC SHUTTLES.

Application filed October 3, 1921. Serial No. 505,057.

To all whom it may concern:

Be it known that I, REINHARD PLUEMACHER, a citizen of the United States, residing at Sunbury, in the county of Northumberland and State of Pennsylvania, have invented certain new and useful Improvements in a Self-Threading Slub Catcher for Automatic Shuttles, of which the following is a specification, reference being had therein

10 to the accompanying drawings.

This invention relates to a self-threading slub catcher for automatic shuttles, and the object of the invention is the provision of means, interposed preferably between the 15 threader block and the bobbin of a shuttle, for automatically receiving the thread or filling from the bobbin, as it is placed in or threaded through the threader block, for evenly engaging the thread or filling to prevent 20 several windings, or heavy places in the yarn resulting from imperfect spinning, being woven into the goods, which weaving of a bunch of several windings or heavy 25 places would cause unsightly imperfections in the cloth.

Another object of the invention is the provision of a slub catcher that is provided with a slot conforming to the shape and height of the slot of a threader block, the slot of the 30 slub catcher being substantially the same width throughout its height.

With this and other objects in view, my invention comprises certain novel combinations, constructions and arrangements of 35 parts as will be hereinafter described, illustrated in the accompanying drawings, and more particularly pointed out in the appended claims.

In the drawings:

40 Figure 1 is a fragmentary, perspective view of a shuttle, showing my improved slub catcher therein.

Figure 2 is a sectional view, taken on line 2-2, Fig. 1, and looking in the direction 45 of the arrows, while

Figure 3 is a similar view of another embodiment of the present invention.

Figure 4 is a perspective view of the slub catcher shown in Fig. 3.

50 Figure 5 is another embodiment of my invention.

Figure 6 is a diagram view, showing the way the thread or filling passes through the slub catcher and at all times, in its passage,

is retained taut, bearing snugly against the 55 wall, or walls, of the slot in the slub catcher.

Referring to the drawings by numerals, 1 designates the shuttle-body, 2 the bobbin, and 3 the threader block. The slub catcher comprises plate 4, formed of fibre or any 60 suitable material. This plate (I use the word "plate" in a generic sense to designate the body of the slub catcher) 4 is beveled from its upper left-hand corner 5, on a gradual curve (Fig. 2), producing the left 65 wall 6 of the slot 7. Starting from the right-hand top corner 8 of the plate 4, the top edge of the plate is beveled inwardly a considerable distance but not so radically as the left-hand edge, until point 9 is 70 reached, then the right-hand wall 10 of the slot 7 conforms to the shape of the wall 6; the slot 7 beginning at point 9 to its bottom is the same width so that the thread or filling 75 11 is bearing tightly against one or both of the walls of the slot as the thread unwinds (Fig. 6) from the bobbin 2. There will be a slight movement of the thread up and down the slot 7 as the thread passes through threader block 3, from bobbin 2, 80 and, of course, the slot 7 must conform to the general slot 12 of the threader block 3 so that the threading of the eye and slub catcher will be accomplished automatically, and also any imperfections in the thread or 85 filling, as it passes from the bobbin to the slub catcher and threader block, will be detected or prevented from entering the goods being woven by the slub catcher stopping the thread, owing to the imperfection of said 90 thread. It will be understood that when a small thread is going through slot 7, as the thread unwinds from the bobbin (Fig. 6), at least one wall of slot 7 will be frictionally 95 engaged at all times, and if the thread is large enough to somewhat tightly fill the slot 7 both walls of said slot will be engaging, generally one wall more tightly than the other, owing to the position of the unwinding thread, from the bobbin, as expressed in Fig. 6, per full and dotted lines, "A" and "B", respectively.

The slot 7 is formed at an angle to the perpendicular axis of the plate 4, shown by dotted lines A-A, Fig. 2, because of the peculiar need for drawing the thread through the slot in a taut condition, to prevent any imperfections from passing into

the cloth, as I have demonstrated by practical experience with my device. The slub catcher is usually held in vertical grooves 13, of shuttle-body 1 by first putting glue 5 in the grooves and then inserting the plate, but, as shown in Figs. 3 and 4, a notch 14 may be formed in one of the side-edges of the plate 4 and then a screw 15 is inserted through the body of the shuttle-body, with 10 the inner end of the screw in notch 14, securely fastening the slub catcher in the shuttle-body 1.

In the embodiment shown in Fig. 5, I have placed auxiliary plates 16 against the 15 primary plate 4, these plates being provided with elongated slots 17, through which screws 18 extend into the plate 4, whereby the plates 16 are adjustable toward each other for increasing or decreasing 20 the width of the slot 7, depending upon the size of the thread or yarn to be employed in the weaving. It will, therefore, be seen that I have provided a slub catcher with a slot and means for controlling the 25 size of the slot.

I use the term "thread" in the foregoing description in a generic sense, meaning any kind of thread, or yarn, or filling, or string, that might be used for any kind of weaving.

30 While I have described the preferred embodiments of my invention, and have illustrated the same in the accompanying drawings, certain minor changes or alterations may appear to one skilled in the art to which 35 this invention relates, during the extensive manufacture of the same and I, therefore, reserve the right to make such alterations or changes as shall fairly fall within the scope of the appended claims.

40 What I claim is:

1. In a device of the character described, the combination of a shuttle body, a bobbin in said shuttle body, a threader block in said shuttle body, a slub catcher in said 45 body between said bobbin and said threader block, said slub catcher comprising a flat one-piece plate provided upon its upper edge at one corner with an inwardly beveled portion and upon its upper edge at the opposite corner with an inwardly beveled por-

tion of less degree than the first beveled portion, the beveled portions terminating at one side of the central vertical axis of the plate in a thread receiving slot, as and for the purposes set forth. 55

2. In a device of the character described, the combination of a shuttle body, a bobbin in said shuttle body, a threader block in said shuttle body, a slub catcher in said body between said bobbin and said threader 60 block, said slub catcher comprising a flat plate-like body having a thread-receiving slot, and adjustable plates on said plate-like body and having their inner edges contiguous to the sides of the slot for controlling the size of the slot, as and for the purposes set forth. 65

3. In a device of the character described, the combination of a shuttle body, a bobbin in said shuttle body, a threader block in said shuttle body, a slub catcher in said body between said bobbin and said threader block, said slub catcher comprising a one-piece plate provided with a thread-receiving slot, plates arranged at opposite sides of said 70 slot for controlling its width, and means on the plates for holding the last-mentioned plates in different adjusted positions, as and for the purposes set forth. 75

4. In a device of the character described, the combination of a shuttle body, a bobbin and a threader block in said body, said body having parallel vertically aligned grooves formed internally thereof, a slub catcher comprising a flat plate-like body 80 having its side edges fitting in said grooves of said body, whereby the slub catcher is retained in position between said bobbin and said threader block, said slub catcher being provided with a vertically extending 85 slot between its side edges, a screw-receiving notch formed in one edge of the plate-like body, said notch fitting within one of said grooves, and a screw carried by the shuttle body and extending into said notch, as and 90 for the purposes set forth. 95

In testimony whereof I hereunto affix my signature.

REINHARD PLUEMACHER.
